Primary Examiner — Jonathan J Han(74) *Attorney, Agent, or Firm* — Greer, Burns & Crain, Ltd(57) **CLAIM**

The ornamental design for footwear as shown and described.

DESCRIPTION

FIG. 1 is a front perspective view of footwear showing my new design;

FIG. 2 is a side view thereof;

FIG. 3 is an opposite side view thereof;

FIG. 4 is a front view thereof;

FIG. 5 is a rear view thereof;

FIG. 6 is a top view thereof; and,

FIG. 7 is a bottom view thereof.

The broken lines in FIGS. 1-7 represent portions of the footwear that form no part of the claimed design. The broken lines which define the bounds of the claimed design form no part thereof.

1 Claim, 3 Drawing Sheets(56)
